(57) **CLAIM**

The ornamental design for an attachment for drawer, as shown and described.

DESCRIPTION

FIG. 1 is a front perspective view of an attachment for drawer showing our new design;

FIG. 2 is a top plan view of the invention illustrated in FIG. 1; FIG. 3 is a front elevation view of the invention illustrated in FIG. 1;

FIG. 4 is a left elevation view of the invention illustrated in FIG. 1;

FIG. 5 is a bottom plan view of the invention illustrated in FIG. 1;

FIG. 6 is a rear elevation view of the invention illustrated in FIG. 1;

FIG. 7 is a bottom perspective view of the invention illustrated in FIG. 1;

FIG. 8 is a front perspective view of the frame element of the invention illustrated in FIG. 1, with some of the environment of FIG. 1 removed and with a transparent top plate;

FIG. 9 is a top plan view of the frame of the invention of FIG. 1, with some of the environment removed;

FIG. 10 is a front elevation view of the frame of the invention of FIG. 1, with some of the environment removed;

FIG. 11 is a left elevation view of the frame of the invention of FIG. 1, with some of the environment removed;

FIG. 12 is a bottom plan view of the frame of the invention of FIG. 1, with some of the environment removed; and,

FIG. 13 is a rear elevation view of the frame of the invention of FIG. 1, with some of the environment removed.

The broken line showing is included for the purpose of illustrating environment and forms no part of the claimed design.
